COMBINED FOOD SLICER, SHREDDER, AND GRATER

Henry J. Talge, Kansas City, Mo., assignor to John C. Hockery, Kansas City, Mo., trustee for Henry J. Talge and Foster L. Talge

Application February 25, 1957, Serial No. 44,986

Term of patent 14 years

(Cl. D89—1)

Fig. 1 is a plan view of a combined food slicer, shredder and grater embodying my new design;

Fig. 2 is a side elevational view of same; and

Fig. 3 is a rear elevational view of same.

The essential features of my design reside in the portions shown in solid lines.

I claim:

The ornamental design for a combined food slicer, shredder and grater, as shown and described.
